UNITED STATES PATENT OFFICE.

CHARLES C. MADSEN, OF CHICAGO, ILLINOIS.

ENVELOPE OPENER.

Application filed July 18, 1923, Serial No. 652,399. Renewed April 19, 1926.

This invention relates to hand-operated tools for opening envelopes, and has reference more particularly to that type of tool which does its work by cutting a narrow strip from one edge of the closed envelope, or trimming off the fold which integrally joins the front and back sides of the envelope; this being accomplished by a relative longitudinal sliding movement of the tool and the envelope.

In one known type of such tools illustrated in Letters Patent to Starkl No. 1,474,856, November 20, 1923, the tool consists of a hollow head and a handle with a longitudinal guide slot extending lengthwise of the handle and across one side of the head, a pair of circular cutting blades mounted in the head with their cutting edges in shear relation in the slot, and a pair of cutter driving rollers mounted coaxially with the cutter blades and in peripheral contact with each other laterally opposite to the cutting points of the blades and serving the double function of driving the cutters through frictional engagement with the envelope drawn between them and clamping the edge of the envelope as the latter is operated upon by the cutters. In such a tool the rotary movement of the cutters is started by forcing the forward end of the envelope or other paper sheet between the contacting peripheries of the driving rollers. Such a tool operates satisfactorily on relatively heavy and stiff stock, but in the case of envelopes or paper sheets of thin and very flexible stock, and especially where the edge of the envelope has become somewhat folded and crumpled in the mails, it is impossible to force the end of the envelope into the nip of the friction driving rollers, and consequently the tool is neither practical nor commercial for use on stock of this character.

The main object of the present invention is to provide a tool of the general character specified which will operate satisfactorily and efficiently on thin flexible stock as well as on relatively heavy and stiff stock; and this object is obtained primarily through the provision of a manually operated device for initially turning the cutting blades so that the advance edge of the envelope is drawn, rather than pushed, into the nip of the cutters; this device being so mounted on the tool that it may be conveniently operated by the forefinger of the hand which

holds the tool. Another object is to simplify and cheapen the cost of production of the tool by a reduction in the number of operating parts and a simplification of the structure; and a still further object is to provide an improved device for supporting the edge of the envelope in the guide slot of the handle and guiding the edge to be trimmed in a line tangential to the overlapping peripheries of the cutter blades.

Other objects and attendant advantages of the invention will be apparent to persons skilled in the art as the same becomes better understood by reference to the following detailed description, taken in connection with the accompanying drawing in which I have illustrated a practical and workable embodiment of the invention, and wherein—

Fig. 1 is a perspective elevation, viewed from the back or rear side thereof, of my improved envelope opener;

Fig. 2 is an inner side elevation of the same;

Fig. 3 is an edge elevation, viewed from the lower side of Fig. 2;

Fig. 4 is an end elevation, viewed from the left of Fig. 2;

Fig. 5 is an enlarged section on the line 5—5 of Fig. 2; and

Fig. 6 is a cross-section through the handle and guide clip taken on the line 6—6 of Fig. 2.

The frame or body of the tool is conveniently made in a casting or stamping, preferably of aluminum, and comprises generally a head portion 10 and a handle 11. The head 10 is slotted throughout substantially its full length and width, forming parallel outer and inner walls 12 and 13, between which the cutters and their associated parts are located. The inner side of the handle 11 is formed with a longitudinal slot 14, the side walls of which are preferably beveled or chamfered, as shown at 15; and the slot 14 is extended through the inner wall 13 of the head, as shown at 14'. The outer sides of the handle 11 may be made concave, as shown at 16, creating shallow depressions which afford an effective grip of the thumb and finger on the handle. Extending between the front and rear walls of the head are a pair of pins 17, preferably having a drive fit within their receiving apertures in the walls, so that they can be readily driven

out by a suitable tool when disassembling the parts. These pins 17 constitute fixed supports in the nature of shafts, on which the cutter blades, their hubs and tensioning devices are rotatably mounted. Rotatable on one of the pins 17 is a hub member 18 formed with a relatively thick flange 18' on one end thereof, and rotatable on the other pin 17 is a hub member 19 formed at the corresponding end with a relatively narrow flange 19'. These hub members 18 and 19 are of a length to just fit between the side walls of the head.

Tightly fitted on the hubs 18 and 19 are the hubs 20' and 21' of a pair of circular steel cutter blades 20 and 21 formed with beveled peripheries, as shown in Fig. 5, which overlap at the transverse center of the slot 14'. The shear relation of the edges of the blades is maintained by parts, next to be described, which operate to press the blade 21 laterally into snug contact with the blade 20 and also serve as a friction drive from one blade to the other in the initial stage of the envelope trimming operation. Inwardly of the hub 21' of the blade 21 is mounted on the hub member 19 a thin spacing washer 22, and on the adjacent end of the blade hub 21' is a flange 21'' and between the washer 22 and the flange 19' of the hub is mounted a disc 23, the same having a drive fit on the hub 19. This disc 23 is of sufficient diameter to project slightly at its periphery beyond the periphery of the head 10 of the tool, as clearly shown in Figs. 1, 4 and 5, and its periphery is preferably roughened, as by grooving or knurling, as shown at 23'. Mounted on the hub 18 and clamped between the hub 20' of the cutter 20 and the flange 18' of the hub 18 are a pair of very thin spring steel washers 24 and 25. The diameter and combined thickness of these washers is such that their peripheral portions enter with a tight fit between the inner side of the driving disc 23 and the opposite side of the cutter flange 21'', whereby, through pressure on said flange they serve to press the cutter 21 into snug shear cooperation with the cutter 20. These discs 24 and 25 also constitute a friction drive from the hub 19 and the parts mounted thereon to the hub 18 and the parts mounted on the latter. Tightly fitted into the longitudinal slot 14 of the handle, and preferably adjacent to the outer end of the latter, is an envelope guiding and supporting clip 26 preferably of substantially U-form and formed with sides which are inwardly bent at their intermediate portions as shown at 26' in Fig. 6, and with outwardly flared end portions 26''. This clip is preferably of spring metal and is designed to assist the user of the tool in maintaining the edge portion of the envelope within the guide slot 14 and also to direct the edge to be trimmed against the cutters on a line, or in a direc-

tion, substantially tangential to the overlapping peripheries of the latter. In using the tool, the handle of the latter is held between the thumb and second finger of one hand, while the edge of the envelope or other sheet to be trimmed, held in the other hand, is entered into the slot 14 and between the sides of the guide clip 26. The envelope is advanced until its forward end enters or approaches the nip of the cutters, whereupon the user, by a few downward strokes of the forefinger on the periphery of the disc 23, starts the cutters into rotation, so that the envelope is positively drawn into the nip of the cutters by the action of the latter thereon, and does not have to be pushed into such engagement with the cutters or into similar engagement with cutter driving discs. After the cutters have thus been manually started in operation through manipulation of the driving disc 23 in the manner described, and the cutting operation has been fairly started, the remainder of the cutting operation may be easily performed by a simple and relative sliding movement of the tool and the envelope.

I claim:

1. An envelope cutter comprising a hollow head and a handle, said handle formed with a longitudinal slot extending across one side of said head to receive and guide an edge of the envelope, a pair of circular cutters journaled in said head with their cutting edges overlapping within said slot, and manually operable means mounted in and projecting beyond the periphery of said head for imparting an initial turning movement to said cutters, whereby to cause said cutters to grip and pull the advance end of the envelope.

2. An envelope cutter comprising a hollow head and a handle, said handle formed with a longitudinal slot extending across one side of said head to receive and guide an edge of the envelope, a pair of circular cutters journaled in said head with their cutting edges in shear relation within said slot, a manually operable cutter-turning device drivingly engaged with one of said cutters and projecting beyond the periphery of said head, and means actuated by said device for simultaneously turning the other cutter in the reverse direction, whereby to cause said cutters to grip and pull the advance end of the envelope.

3. An envelope cutter comprising a hollow head and a handle, said handle formed with a longitudinal slot extending across one side of said head to receive and guide an edge of the envelope, a pair of circular cutters journaled in said head with their cutting edges in shear relation within said slot, a manually operable cutter-turning disc coaxially and drivingly engaged with one of said cutters and having its periphery projecting beyond

the periphery of said head, and friction means actuated by said disc for simultaneously rotating the other cutter in the reverse direction, whereby to cause said cutters to grip and pull the advance end of the envelope.

4. An envelope cutter comprising a hollow head and a handle, said handle formed with a longitudinal slot extending across one side of said head to receive and guide an edge of the envelope, a pair of pivot pins mounted in and crosswise of said head, a pair of cutter discs rotatable on said pivot pins, respectively, with their cutting edges in shear relation within said slot, a manually operable cutter-turning disc rotatably mounted on one of said pivot pins laterally opposite to, and drivingly engaged with, one of said cutters, said disc having its periphery projecting beyond the periphery of said head, and friction means actuated by said disc for simultaneously turning the other cutter in the reverse direction, whereby to cause said cutters to grip and pull the advance end of the envelope.

5. An envelope cutter comprising a hollow head and a handle, said handle formed with a longitudinal slot extending across one side of said head to receive and guide an edge of the envelope, a pair of pivot pins mounted in and crosswise of said head, a pair of cutter discs rotatable on said pivot pins, respectively, with their cutting edges in shear relation with said slot, means for pressing the cutting peripheries of said cutters laterally into snug contact with each other, a cutter-turning disc rotatably mounted on one of said pivot pins laterally opposite to, and drivingly engaged with, one of said cutters, said disc having a roughened periphery projecting beyond the periphery of said head and adapted to be engaged by a finger of the operator to turn the same, and a friction drive between said disc and the other cutter serving to simultaneously turn the latter in the reverse direction, whereby to cause said cutters to grip and pull the advance end of the envelope.

6. An envelope cutter comprising a hollow head and a handle formed with a continuous

guide slot extending lengthwise of the handle and across one side of said head, a pair of pivot pins mounted in and crosswise of said head, a pair of hubs rotatable on said pivot pins, respectively, a pair of cutter discs fast on said hubs, respectively, with their cutting edges in shear relation with said slot, co-operating devices on said hubs, respectively, serving to press the cutting periphery of one of said cutters laterally into snug contact with the cutting periphery of the other, a cutter turning disc fast on one of said hubs drivingly engaged with the cutter mounted on the latter, said disc having a roughened periphery projecting beyond the periphery of said head and adapted to be engaged by a finger of the operator to turn the same, and a friction drive between said hubs serving to simultaneously turn the other cutter in the reverse direction, whereby to cause said cutters to grip and pull the advance end of the envelope.

7. An envelope cutter comprising a hollow head and a handle formed with a continuous guide slot extending lengthwise of the handle and across one side of said head, a pair of circular cutter blades journaled in said head with their cutting edges overlapping within said slot, and a substantially U-shaped clip for guiding and supporting the edge of the envelope to be trimmed mounted in said slot adjacent to the end of said handle remote from said head.

8. An envelope cutter comprising a hollow head and a handle formed with a continuous guide slot extending lengthwise of the handle and across one side of said head, a pair of circular cutter blades journaled in said head with their cutting edges overlapping within said slot, and a clip for guiding and supporting the edge of the envelope to be trimmed mounted in said slot, said clip having sides inwardly bent at their intermediate portions to engage with the opposite sides of an envelope inserted between them and outwardly splayed end portions to guide the edge of the envelope into said clip.
